(57) **CLAIM**

The ornamental design for a pocket pen, as shown and described.

DESCRIPTION

FIG. 1 is a perspective view showing our new pocket pen;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view showing the cap portion of the pen separated from the barrel portion thereof; and,

FIG. 9 is a perspective view showing the pen in its operative writing mode.

The portions shown in broken lines in FIGS. 1, 2 and 4-9 are for illustration only and form no part of the claimed design.
